UNITED STATES PATENT OFFICE

FRANK A. FAHRENWALD, OF CHICAGO, ILLINOIS

FURNACE CONVEYER DISK

Application filed December 17, 1928. Serial No. 326,513.

This invention relates to heat treating furnaces and is illustrated herein as embodied in a conveyer for use in carrying through the furnace objects and products to be treated. A conveyer of the same general type as that which forms the subject matter of this invention is disclosed and claimed in United States Letters Patent No. 1,539,833, granted to me on the 2nd day of June, 1925, and another is set forth in United States Letters Patent No. 1,623,469, granted to me on the 5th day of April, 1927.

In the first of the aforescribed patents there is disclosed a conveyer disk comprising an outer rim, a plurality of spokes extending inwardly from the rim and segmental members formed on the inner ends of the spokes. Owing to the fact that the segmental members are formed separately from one another, the conveyer allows a certain amount of contraction and expansion, which occurs owing to the use to which the conveyer is put. In the second patent, there is disclosed a hollow tubular metal body having conveyer disks mounted on it, and in this construction there is within the disk itself no provision for cooling.

While both of the foregoing constructions have proved and are still proving eminently satisfactory as commercial and engineering projects, it has been found that after long continued usage of conveyers constructed in accordance with the disclosures of the prior patents that the rims of the conveyer crack and break thereby rendering such conveyer disks inoperative and subject to replacement. Replacing the disks is a costly operation and one which is to be avoided if possible, and it is in view of this tendency of the prior rims to crack and break upon occasion, and to overcome the necessity of replacing them, that the present invention has been devised. Accordingly, an important object of the present invention consists in the provision of an improved conveyer disk constructed and arranged freely to permit expansion and contraction of the rims of the disks without setting up any severe internal strains or stresses.

A feature of the invention which is conducive to the accomplishment of the recited

object consists in connecting the rim portions of the disks to the hub portions by means of spokes which are constructed in such a manner that they will not oppose expansion and contraction of the rim portions. As illustrated herein this characteristic of the invention is carried out by offsetting the spokes in the direction of the axes of the disks. It is to be recognized, of course, that it is old and well-known to provide wheels, etc., the spokes of which are convoluted in the plane of the wheel, but such a form of construction fails utterly to obtain the merits of the present invention in which the convolutions are at right angles to the plane of the wheel or disk as contrasted with being within such plane.

A further feature of the invention consists in the provision of a conveyer disk of the type herein described that is simple in design and construction and compact in its arrangement. To the end of carrying out this feature, the disk is provided with a hub portion of approximately the same width as the outer rim portion of the disk and these two members are assembled in such a manner that the convolute spokes extend from one end of the rim diagonally to the opposite end of the hub, whereby they are disposed between the two planes that define the opposite sides of the rim.

Another feature of the invention, which lends itself to the accomplishment of the recited object, consists in the provision of a furnace conveyer disk that is substantially of uniform thickness throughout. By means of such a provision, uniform cooling and heating of the disk is permitted to take place and likewise free expansion and contraction without setting up severe internal stresses and strains at points where there would otherwise be a concentration of the metal of the disk.

Still other objects and features of the invention will become apparent from a reading of the specification in the light of the accompanying drawings—in which—

Figure 1 is an assembled view showing the interior of a heat treating furnace equipped with conveyer disks;

Figure 2 is an enlarged sectional view of the conveyer disks shown in Figure 1;

Figure 3 is a still further enlarged view of a single conveyer of the type shown in Figure 1; and

5 Figure 4 is a view in section taken along the line 4—4 of Figure 3.

Inasmuch as heat treating furnaces and the purposes and objects thereof are old and well-known, no discussion will be devoted 10 to such topics, nor will the construction of such a furnace be described other than to mention that, as shown in Figure 1, the furnace comprises an outer casing 10 of refractory material having mounted transversely thereof a series of rotatable axles 12 which carry the conveyer disks or elements 16.

The conveyer disks 16 are secured to the axles 12 in a satisfactory manner in order 20 that they will rotate with the axles, and, as illustrated herein, the connection between the two parts comprises, as shown in Figure 3, a radially extending pin 18 that is carried by the axle 12. The disk 16 has its hub portion provided with a transverse groove 20 that is 25 large enough to receive the pin 18, and intermediately between the opposite ends of the groove 20 there is formed a communicating circumferential slot 22 that is likewise of sufficient size to accommodate the pin 18.

30 In operation, the disk is slipped over the axle and moved endwise thereon until it meets the pin 18 whereupon the slot 20 is brought into registry with the pin and the disk is pushed over the pin until the latter registers with the circumferential slot 22 at which instant the disk is rotated relatively to the axle to seat the pin 18 firmly within the slot 22. The slot extends in a direction opposite to that of the rotation of the disks whereby there is no tendency or opportunity for 40 the disks to become loose during operation of the furnace.

45 As shown in Figure 2, the axles or shafts 12 are surrounded, between the conveyer disks 16, with segmental sleeve portions 14 which serve both to space and to strengthen the conveyer disks.

50 Turning now to the conveyer disks themselves and more particularly to the design and construction thereof, it will be seen by an inspection of Figure 4 that each disk comprises a flat outer load engaging rim 24, an inner hub portion 26, which, by the way, 55 is formed with the groove 20 and slot 22 therein, and connecting portions, that may be termed spokes, 28 extending between the hub and the rim to connect the two parts together. The spokes 28, it will be observed, 60 extend from one end or side of the rim portion 24 inwardly toward the hub and are thence offset in the direction of the central axis of the axle 12 to extend diagonally to the opposite end or side of the hub 26. Thus, 65 the spokes or connecting portions are con-

voluted in the direction in which extends the central axis of the support or shaft upon which the conveyer disk is mounted.

70 While the conveyer disks have been described as being provided with spokes it is to be understood that the disk in one aspect comprises an outer rim and a dished-out body portion that is cut away in order to provide the spokes. In view of this fact, the spokes are not to be considered as limitations in the invention for it is realized that the connecting portion of the disks might well be made without openings and hence without spokes and still be susceptible of carrying out the major objects and features of the invention. 75

80 It will be observed that the disk illustrated and disclosed herein is of substantially uniform thickness throughout and is formed of a continuous sweep of metal. The lines of junction between the body portion of the disk 85 and the hub and rim portions thereof, are rounded to increase the strength of the conveyer and to decrease the tendency to warp or check upon sudden expansion or contraction. Furthermore it will be observed that 90 the dished out body portion extends from one end (as contrasted with the side) of the rim to the opposite end (again as contrasted with the side) of the hub portion, which permits the uniform thickness to be maintained 95 throughout and again tends to decrease warpage and breakage from sudden temperature fluctuations. Thus it will also be appreciated that the entire disk is formed of one continuous sinuous section of approximately uniform diameter throughout. 100

105 Although the invention has been described herein with particular reference to conveyer disks for use in connection with heat treating furnaces, it is to be recognized and clearly understood that the invention may be used in connection with other similar and analogous apparatus, and that certain changes in design and construction of the disks may be made by the exercise of mechanical skill without in the least departing from the scope of the invention as set forth in the appended claims.

110 Having thus described my invention, what I claim as new and desire to secure by United States Letters Patent, is:

115 1. A furnace conveyer disk comprising, in combination, a rim, a hub, and a connecting portion extending from one end of the rim diagonally inward to the opposite end of the hub.

120 2. A conveyer comprising, in combination, a cylindrical support, and a plurality of spaced conveyer disks mounted upon the support, each of said disks comprising a rim, and a connecting portion extending from one end of the rim diagonally in the direction of the cylindrical support.

125 3. A furnace conveyer comprising, in combination, an elongated support having a cen-

tral axis, a rim mounted to surround the support, and means connecting the rim to the support, said means being arranged to extend inwardly from one end of the rim toward the support and thence being offset in the direction of the central axis of the support.

4. A furnace conveyer comprising, in combination, a hub, a rim, and a dished-out body portion connecting the hub to the rim, said body portion being cut away to provide a plurality of spokes extending from the hub.

5. A conveyer disk comprising, in combination, a hub, a rim, and a body portion joining the hub to the rim, said hub, rim, and body portion all being of a substantially uniform thickness.

6. A conveyer disk comprising in combination a hub, a rim and a body portion, joining the hub to the rim, said hub, rim and body portion being formed from a single sweep of metal of a substantially uniform thickness throughout.

7. A furnace conveyer disk having a hub member, a web member, and a rim member all formed of one continuous, sinuous section of approximately uniform thickness throughout.

8. A furnace conveyer disk having a hub member, a rim member, and a web member extending from one end of the hub to the opposite end of the rim, said hub, rim, and web members being formed of one continuous, sinuous section of metal.

9. A furnace conveyer disk comprising a hub portion, a rim portion, and a connecting portion uniting said hub and rim portions; said connecting portion being inclined to the axis of the disk in radial planes embracing said axis, and being of substantially uniform thickness with said hub and rim portions.

10. A furnace conveyer disk comprising spaced hub and rim portions, and a connecting portion uniting said hub and rim portions; said connecting portion being inclined to the axis of the disk in radial planes embracing said axis and being substantially uniform thickness with said hub and rim portions, and merging with said hub and rim portions at axially presented margins thereof.

50 Signed at Chicago, Illinois, this 11th day of December, 1928.

FRANK A. FAHRENWALD.
